UNITED STATES PATENT OFFICE.

WILLIE H. CRUMMEY, OF BAXLEY, GEORGIA, ASSIGNOR OF ONE-HALF TO HENRY C. CRUMMEY, OF BAXLEY, GEORGIA.

COMPOUND TOOL.

1,344,264.

Specification of Letters Patent. Patented June 22, 1920.

Application filed January 9, 1917. Serial No. 141,384.

To all whom it may concern:

Be it known that I, WILLIE H. CRUMMEY, a citizen of the United States, residing at Baxley, in the county of Appling and 5 State of Georgia, have invented certain new and useful Improvements in Compound Tools; and I do hereby declare the following to be a full, clear, and exact description of the invention, such as will enable others 10 skilled in the art to which it appertains to make and use the same.

This invention relates to new and useful improvements in compound tools and the principal object of the invention is to provide 15 a combination watch maker's tool adapted for various uses and so constructed as to take the place of several of the ordinary tools now in use so that the user will have a number of tools at his command 20 without having to lay down one and pick up another tool thus causing considerable loss of time.

A further object of the invention is to provide 25 a device which is adapted to be used as a truing caliper and also to provide a device for use as a glass cutter for cutting circles and similar figures.

Still another object of the invention is to provide 30 a punch for removing the jewels of the balance wheel which is arranged to avoid danger of breaking the jewel.

With these and other objects in view the invention consists in the novel combination and arrangement of parts which will be 35 fully set forth in the following specification and accompanying drawings, in which:—

Figure 1 is a side view in elevation of a watch maker's tool constructed in accordance with this invention.

40 Fig. 2 is a view from the opposite side of Fig. 1 showing portions of the device in section to more clearly illustrate the details of construction.

Fig. 3 is an edge view of the device, 45 Fig. 4 is a longitudinal sectional view on line 4—4 of Fig. 2, and

Fig. 5 is a detail view showing pointer and mounting for the same.

Referring to the drawings, 1 designates 50 one of the handles of the device while the numeral 2 designates the coöperating handle. Each of these handles is formed at one end with a head 3 having a central aperture therethrough for the reception of the pivot bolt 4 by means of which the device is

held in assembled position and formed on the handle 1 is a jaw member 5, while the jaw member 6 is formed on the handle 2 thus forming a device which when the handles are closed will move the jaw members to closed position. Threaded in the jaw members are suitable thumb screws 7, the heads 8 of which are knurled to form a gripping surface by which the same may be turned while the inner adjacent ends of said 65 screws designated by the numeral 9 are provided with suitable recesses receiving jewel bearings for rotatably supporting the staff of the balance wheel of a watch when the same is being trued. A suitable set screw 10 70 is threaded into one side of one of the jaw members and extends through a slot 11 formed in the truing gage plate 12 which is arranged to coöperate with the screws 7 in truing a balance wheel. A pointer 10^a is 75 pivoted as at 10^b to the gage plate 10 and is adapted to swing at right angles to the plate and engage the balance wheel being trued, the free end of the pointer being curved downwardly as at 10^c for engaging 80 the balance wheel. The downturned end 10^d is pivoted as at 10^d to the pointer so that the same can swing toward the rim of the balance wheel when gaging wheels of different 85 diameters. Formed on each of the jaw members are suitable extensions 13 and 14 respectively and the jaw member 13 is apertured to receive a suitable pin 15 while a similar aperture 16 is formed near the outer end of the jaw member 13 and is arranged 90 to aline with a punch 17 which is fitted into an opening 18 formed in the jaw member 14 which punch is removably secured in place by means of a suitable latch member 19. This punch is used for removing the jewels 95 from a watch and it will be seen that when the device is manipulated the punch will aline with the opening 16. Removably secured in an aperture 20 formed in the extreme end of the extension 14 is a pin 21 100 having formed intermediate its ends a head 22, which is arranged to engage the inner surface of the extension 14 to limit the inward movement of the pin. The inner end of the pin has formed integrally therewith a barrel punch 23 which coöperates with the transversely curved surface 24 formed on the inner face of the extreme forward end of the extension 13. The curved surface 24 of the jaw is arranged transversely of 110

the extension 13 and is arranged so as to form a suitable rest or anvil for the watch barrel, when the punch 23 is being used to make a catch in the barrel for the spring. 5 The surface 24 is curved so as to fit any size barrel.

Formed in the end of the handle member 1 opposite that having the jaw member 5 formed thereon is a suitable bore 25 for 10 the reception of a suitable centering pin which is arranged to act as a center when the device is used as a compass. A bore 26 is formed in the coöperating handle member 2 opposite the end on which the head 6 15 is formed and is adapted to receive the shank of a glass cutter so as to hold the same in operative relation with the point hereinbefore referred to. Formed in the handle member 2 adjacent the end having the opening 26 formed therein is a plurality of notches 27 which are graduated in size as shown to receive glass of different thicknesses to grip the same when being broken after having been cut. In order to limit 20 the closing of the jaws and handle members a suitable set screw 28 passes through the handle member 1 and the inner end of said set screw engages the inner side of the handle member 2 as will be clearly seen 25 upon reference to Figs. 1 and 2 of the drawings.

Pivottally connected as at 29 to the handle member 1 is a gage plate 30 which is slotted as at 31 to receive the shank of a set screw 32 which is adapted to be threaded into the handle member 2 and this gage plate is provided with a plurality of graduations 33 for coöperation with a V-shaped mark 34 formed on the handle member 2 so as to indicate the distance between the center and 35 the glass cutter when the device is used to 40 cut glass. In order to provide a wire cut-

ter each of the heads 3 is provided with a suitable notch 35 through which the wire is passed and it will be seen that upon closing 45 the handles the same will be cut.

While in the foregoing there has been shown and described the preferred embodiment of this invention, it is to be understood that such changes may be made in the 50 combination and arrangement of parts as will fall within the spirit and scope of the invention as claimed.

What is claimed is:—

A device of the class described comprising 55 a pair of pivotally connected handles, heads formed on the forward ends of the handles, jaw members formed integrally with the heads, adjustable supports carried by the jaws and arranged in direct alignment with each other, bearings formed on the adjacent ends of the supports and arranged to rotatably receive the terminals of the balance staff of a watch, a slotted plate mounted on one of the jaws, a set 60 screw carried by the jaw and extending through the slot of the said slotted plate and arranged to engage the outer surface of the plate to hold the same in adjusted position, a pointer pivotally secured to the lower 65 end of the plate and arranged to swing at right angles thereto, the outer end of the pointer being turned downwardly for engaging the balance wheel, said downturned end being pivotally connected to and arranged to swing at right angles to the plate, 70 as and for the purpose specified.

In testimony whereof I affix my signature in presence of two witnesses.

WILLIE H. CRUMMEY.
